UNITED STATES PATENT OFFICE.

JOHN E. McMINN, OF LOUISVILLE, KENTUCKY, ASSIGNOR TO PEERLESS MANUFACTURING COMPANY, OF LOUISVILLE, KENTUCKY, A CORPORATION OF DELAWARE.

DESIGN FOR A FIREPLACE HEATER.

Application filed September 11, 1924. Serial No. 10,743. Term of patent 3½ years.

To all whom it may concern:

Be it known that I, JOHN E. McMINN, a citizen of the United States, residing at Louisville, in the county of Jefferson and State of Kentucky, have invented a new, original, and ornamental Design for Fireplace Heaters, of which the following is a specification, reference being had to the accompanying drawing, forming part hereof, wherein—

Fig. 1 is a front elevation and Fig. 2 an end view of a fireplace heater exhibiting my new design.

I claim:

The ornamental design for a fireplace heater, as shown.

JOHN E. McMINN.
